DESIGN FOR A SHOCKPROOF HEAD FOR AN X-RAY APPARATUS

Edward B. Graves, Fort Mitchell, Ky., assignor to
The Kelley-Koett Manufacturing Company, In-
corporated, Covington, Ky., a corporation of
Ohio

Application January 21, 1935, Serial No. 54,977

Term of patent 7 years

To all whom it may concern:

Be it known that I, Edward B. Graves, a citizen
of the United States, residing at 64 Arcadia
Drive, Fort Mitchell, in the county of Kenton and
State of Kentucky, have invented a new, orig-
inal, and ornamental Design for a Shockproof
Head for X-ray Apparatus, of which the follow-
ing is a specification, reference being had to the
accompanying drawing, forming part thereof.

Fig. 1 is a side elevational view of a shockproof
head for an X-ray apparatus, showing my new
design, and

Fig. 2 is an end elevational view thereof.

I claim:

The ornamental design for a shockproof head
for an X-ray apparatus, substantially as shown.

EDWARD B. GRAVES.
